ATTACHÉ CASE

Otto Mayer, R.F.D. 2, Lake Carmel, N.Y.

Filed Oct. 15, 1959, Ser. No. 57,954

Term of patent 14 years

(Cl. D87—5)

FIG.1

The characteristic feature of my design resides in the three-earred overlying layer of covering material and associated rivet heads on the sidewalls, said ears being connected by a straight line parallel to and midway between the edges of the sidewall, all as shown.

I claim:

The ornamental design for an attaché case, substantially as shown and described.
